UNITED STATES PATENT OFFICE.

WILLIAM E. SIMPSON, OF HIGHLAND PARK, MICHIGAN.

HOIST.

Application filed September 10, 1920. Serial No. 409,435.

To all whom it may concern:

Be it known that I, WILLIAM E. SIMPSON, a subject of the King of Great Britain and Ireland, residing at Highland Park, in the 5 county of Wayne and State of Michigan, have invented certain new and useful Improvements in Hoists, of which the following is a specification, reference being had therein to the accompanying drawing.

10 The invention relates to hoists and is particularly adapted for use in cranes and the like in which the hoists are operated by electric motor or by any suitable form of fluid pressure motor. One of the objects 15 of the invention is to provide a simple and effective brake for controlling the movements of the load and maintaining the same in suspension when the motive power is cut off. Another object is the provision of 20 means automatically actuating the brake to govern the rate of speed of the motor, and further the provision of means for normally actuating the brake, which is adapted to be 25 manually released when the motive power is supplied and automatically applied when the motive power is cut off. Still another 30 object is the provision of means for securing the circulation of air around the braking elements for cooling the same. Still further objects of the invention reside in the novel arrangements and combinations of parts as more fully hereinafter set forth.

In the drawings:

Figure 1 is a side elevation of a hoist 35 embodying my invention;

Figure 2 is a sectional plan view thereof;

Figures 3, 4, 5 and 6 are cross sections respectively on the lines 3—3, 4—4, 5—5 and 6—6 of Figure 2;

40 Figure 7 is an elevation showing a portion of the manually operable mechanism, for releasing the brake;

Figures 8, 9 and 10 are central sections through the control mechanism, showing the 45 parts in different adjusted positions.

Figure 11 is an enlarged sectional view through the casing and mechanism to the right of the planetary gearing illustrated in Figure 2.

50 As shown, particularly in Figures 1, 2 and 3 the main frame of the hoist comprises a pair of semi-cylindrical housings 1 and 2 secured to each other on the vertical central line of the hoist, as by the bolts 3, the upper 55 adjoining edges of these housings being suitably secured to the hook 4, by which the

hoist is suspended. 5 and 6 are circular diaphragms at the outer ends of the housings 1 and 2, having the hollow bosses 7, in which is journaled the hollow hoist drum 60 shaft 8. 9 is a motor housing suitably secured to the circular diaphragm 5 as by means of the studs 10. 11 is a housing suitably secured to the circular diaphragm 6 as by means of the bolts 12. 65

13 is a hoist drum having its external peripheral surface formed with spiral grooves 14 for receiving the flexible hoisting element 15, which in the present instance is a rope. The hoist drum 13 has a pair of hubs 16 non-rotatably secured upon the drum shaft 8. For rotating the hoist drum 13 from the motor 17, which is mounted in the motor housing 9, there is a drive shaft 18 connected to the motor and extending 70 through the drum shaft 8, and driving the same through the planetary gearing 19 in the housing 11. The planetary gearing comprises the annular gear 20 secured to a cylindrical flange 21 upon the drum shaft, an 75 annular gear 22 secured to the housing 11, and planetary pinions 23 meshing with the annular gears 20 and 22 and with the drive pinion 24 upon the drive shaft 18. The annular gears 20 and 22 have different numbers of teeth so that for every complete revolution of the planetary pinions 23 within the annular gears, the drum shaft will be rotated through an angle equal to the number of teeth difference between the two annular gears. 80 90

For controlling the rate of speed of the motor 17, the following construction is provided: Upon the outer end of the drive shaft 18 is formed a flange 25 to which is 95 secured the brake driving member 26, as by means of the bolts 27. This brake driving member has the cylindrical flange 26' having in its outer periphery slots or key-ways in which the series of brake driving disks 28 engage in a manner well known in the art and alternately arranged with these brake driving disks are the series of disks 29 which are held stationary by key-like projections 30 integral with the housing 11, which projections engage in peripheral slots or key-ways in said disks. Both series of disks are 100 axially movable or in other words movable in a direction parallel to the drive shaft 18. 105

A disk 31 of slate or other insulating material which forms the base of the electric controller to be hereinafter described is se- 110

- cured to the outer faces of the projections 30 by the screws 32. In the center of this disk, is secured by screws 33, a flanged bushing 34 and within this bushing is slidably 5 mounted a brake applying sleeve 35, one end of which normally bears against the outer brake disk 29. In the inner end of the sleeve 35 are two diametrically opposed slots 36 which engage with the guides 37 mounted 10 upon the pin 38 which is securely held in the bushing 34, whereby the sleeve 35 is prevented from rotation while capable of end-wise movement. Upon the pin 38 is secured one end of the bolt 39, the other end of 15 which is threaded to receive the nut 40. Around the bolt 39 is arranged a helical spring 41, one end of which abuts against the nut 40 while the other end bears upon the projecting ends of the pins 42 secured 20 within the sleeve 35 so that the inner end of said sleeve is yieldably pressed against the outer brake disk 29 by the spring 41 with a force depending upon the location of the nut 40 relative to the bolt 39, thereby tending 25 to force the brake disks 28 and 29 into contact with each other and toward the outwardly-extending annular flange 43 upon the cylindrical flange 26' of the driving member 26.
- 30 The reaction of these disks instead of being taken directly upon the annular flange 43 is received by a pair of diametrically opposite buttons 44 secured to the faces of governing weights 45 which are threaded internally to engage the screws 46 fixedly secured in the annular flange 43 and extending transversely thereof. Each of the governor weights 45 is normally held in the position shown by dotted lines in Figure 4, by means 35 of a spring 47, one end of which is attached to a lug 48 upon the weight and the other to an adjustable eyebolt 49 secured to a bracket 50 upon the annular flange 43 and preferably integral therewith. As shown the screws 46 have left hand threads and the arrangement is such that when the governor weights 45 are caused to move outward to the position shown by full lines in Figure 4, due to centrifugal force caused by the rotation 40 of the drive shaft 18 with the driving member 26 and governing weights 45 they rotate upon the screws 46 and move longitudinally thereon and away from the annular flange 43, thereby causing the buttons 44 to press against the inner disk 28 and move 45 both the series of driving disks 28 and stationary disks 29 into contact with each other to a degree depending upon the speed of rotation.
- 50 Synchronism of the movement of the two governing weights 45 is insured by the equalizer ring 51 which is rotatably supported upon the periphery of the boss 52 upon the circular diaphragm 53 integral 55 with the housing 11 and within which the

outer end of the drive shaft 18 is journaled. This equalizer ring 51 is connected at diametrically opposite points by links 54 to the governor weights 45.

Upon the outer end of the sleeve 35 is a flanged collar 55 secured thereon by the nuts 56 and prevented from rotating by the key 57. Between the inner end of this collar and the outer end of the bushing 34 is a carrier 58 rotatably mounted upon the sleeve 35 and carrying brushes 59 of the controller, suitable insulator washers being interposed in a well-known manner. Upon the adjoining faces of the carrier 58 and collar 55 are double helical or cam like projections 60 as shown in Figure 7 which projections are so arranged that by rotating the carrier 58 in one direction or the other by means to be hereinafter explained the collar 55 is forced outward and away from the carrier 58 so as to withdraw the sleeve 35 against the action of the spring 41 thereby manually releasing the brake.

The arrangement for controlling and reversing the hoist motor 17, comprises a series of contacts 61 and 62 which are electrically connected to the motor and are frictionally engaged by fingers of any ordinary construction upon the brushes 59. Suitable rheostats are interposed in a well-known manner and protection of the motor from overload is provided for in the form of cartridge fuses 63 attached to the base or disk 31.

The rotation of the brush carrier 58 is effected through movement of the manually operable lever 64 and pendant operating cords 65 in the following manner: The lever 64 is rotatably mounted within a boss 66 upon the cover 67, which is hinged to the housing 11 and suitably held in closed position. 68 is an annulus within the cover 67 and non-rotatably secured to the lever 64, this annulus being provided with diametrically opposite radially projecting jaws 69, 70, 71 and 72 arranged in pairs and shown more in detail in Figures 5, 8, 9 and 10. To the brush carrier 58 is attached a ring 73 on the outer periphery of which is mounted a ring 74 keyed thereon, so as to be capable of sliding axially but prevented from rotating in relation thereto. The ring 74 has two diametrically opposite projections 75 and 76 which are adapted normally to extend between and engage with the pairs of jaws 69 and 70, 71 and 72 respectively, so that when one or the other of the operating cords 65 is pulled downward, the consequent rotary movement of the hand lever 64 is imparted to the brush carrier 58, thereby first releasing the brake by withdrawing the sleeve 35 as previously described and then causing the contact fingers of the brushes 59 to cooperate with either the contacts 61 or 62 so as to energize the motor 17 and to cause the hoist drum 13 to be rotated in one

direction or the other depending on which of the operating cords is pulled.

The ring 74 is held in its normal position as shown in Figure 9 by the yoke 77, the 5 fork ends 78 of which engage in a groove 79 in the ring. This yoke is mounted on the end of a rod 80 which is slidably supported in bearings 81, 82 and 83, the former bearing being upon the motor housing 9 and the 10 latter two bearings upon the housing 11. This rod is maintained in a neutral or central position by two springs 84 and 85 surrounding the rod, the spring 84 bearing against the collar 86 fixed upon the rod and one side of the supporting bearing 83, while the spring 85 bears against the other side of the supporting bearing 83 and against the yoke 77, these springs being of equal 15 strength.

Upon the rod 80 is slidably mounted a rack 87 having teeth adapted to engage the grooves 13 of the hoist 14, these grooves being of such depth as to receive these teeth in addition to the flexible hoisting element 20

15. By this arrangement, the rack 87 which travels back and forth as the drum is rotated in one direction or the other serves to maintain the hoisting element 15 within the grooves at all times regardless of side pull.

The rack 87 is prevented from rotating by the inner faces of the slot 88 within which it projects, this slot being formed in the semi-cylindrical housings 1 and 2 near their corresponding lower edges.

The brush carrier 58 is normally held in the neutral or central position by a coil spring 89 shown more clearly in Figure 6 and having its free ends turned outward so as to embrace between them a projection 90 upon the ring 73 and a projection 91 upon the collar 55. Stops 92 and 93, formed of pairs of lock nuts, are provided upon the rod 80, these stops being adjustable to come in the path of the rack 87 and be operated 25 thereby, so as to cause longitudinal movement of the rod 80 in one direction or the other as the hoist block upon the flexible hoisting element 15 reaches its upper or lower limit of travel. By this means, when 30 the operating lever 64 is held in one or the other working position causing the drum to be rotated and the rack 87 comes against one or the other of the stops and imparts longitudinal movement to the rod 80, the 35 yoke 77 is carried with it and the ring 74, thereby moved into one or the other of the positions shown in Figures 8 and 10 causing longitudinal displacement of the projections 75 and 76 in relation to the lugs 69, 70, 40 71 and 72.

It will be observed that these lugs are arranged in different planes in a longitudinal direction. The diametrically opposite lugs 45 69 and 72 being in a common plane while the diametrically opposite lugs 70 and 71

are in a common plane offset therefrom. The arrangement is such that when the operating lever is rotated in a clockwise direction, which in the present case is assumed to be the lowering direction, the driving of the 70 ring 74 and through it the brush carrier 58, is effected by pressure of the lugs 69 and 72 against the projections 75 and 76 on the ring while when the lever is rotated in a counter-clockwise direction so as to cause the load 75 to be raised, the driving is effected through the other pair of lugs 70 and 71. When, therefore, the load is being lowered and the hoist block reaches the predetermined lower limit of its movement, the yoke 77 and ring 80 80 are moved from the central position as shown in Figure 9 to the position shown in Figure 8 which brings the projections 75 and 76 clear of the lugs 69 and 72 and allows the brush carrier 58 to be returned to the 85 neutral or central position under the action of the spring 89 so as to cut off the current. This rotation of the brush carrier also permits of the inward movement of the sleeve 35 to apply the brake. It will be understood 90 from Figure 8 that the lugs 70 and 71 are still in a position to engage with the projections 75 and 76 so as to move the brush carrier to the raising position when the movement of the operating lever is reversed. Similarly when the load is being raised and the hoist block reaches its upper limit of travel, the yoke 77 and ring 74 are moved into the position indicated in Figure 10 95 which brings the projections 75 and 76 clear of the lugs 70 and 71 and releases the brush carrier and brake, but the lugs 69 and 72 are still in a position to engage with the projections and move the brush carrier to the 100 lowering position, when the operating lever is moved in the proper direction. It will be readily understood that by the arrangement above described the brush carrier is returned instantaneously to the neutral position 105 when the stop motion is operated, thereby giving a quick break of the current and avoiding burning and flashing at the contacts.

By the employment of the centrifugal brake governing device in conjunction with the hand operating device for releasing the brake wholly or partially while at the same time controlling the current supply, a much greater precision of control is obtained than is possible by electrical means alone, and the whole apparatus may be so proportioned and adjusted that the brake is automatically applied when a dangerous or objectionable rate of speed is reached, even though the control may be in a "full on" position.

Another important feature of my invention resides in the means for securing a circulation of air around the braking elements to assist in cooling the same. As shown, the housing 11 is provided with suitable aper-

tures 94 and the outer brake disk 29 and controller base or disk 31 are also provided with suitable apertures 95 and 96 respectively, while the hub of the operating lever 5 64 has an aperture 97 therein for the passage of air which is caused to pass around the brake disks by means of the vanes 98 upon the governor weights 45.

What I claim as my invention is:

- 10 1. In a hoist, the combination with a driving shaft, of a series of rotary brake disks secured to said shaft, a series of stationary brake disks alternating with said rotary disks, all of said disks being capable 15 of axial movement, means for applying spring pressure to one side of said disks, a rotating abutment on the opposite side of said disks, means for relieving said spring pressure, and a centrifugal device adapted 20 to vary the position of said rotary abutment according to the speed of rotation.
2. In a hoist, the combination with a driving shaft, of a series of rotary brake disks secured to said shaft, a series of stationary brake disks alternating with said 25 rotary disks, all of said disks being capable of axial movement, a spring-operated pressure element on one side of said disks, a rotating element on the opposite side of said 30 disks, a movable abutment on said rotating element, means for withdrawing said pressure element, and a centrifugal device for varying the position of said abutment according to the speed of rotation of said 35 driving shaft.
3. In a hoist, the combination with a housing, of a driving shaft rotatably mounted therein, an annular flange non-rotatably mounted upon said driving shaft, 40 a brake element non-rotatably mounted on said driving shaft and at the side of said annular flange, a second brake element non-rotatably secured to said housing and at the side of said first-mentioned brake element and adapted to engage the latter, a 45 governor weight controlled by the rate of rotation of said driving shaft, and means upon said annular flange adapted to be moved by said governor weight to force the 50 brake elements into contact with each other when said governor weight moves away from said annular flange upon rotation of said governor weight relative to said annular flange.
- 55 4. In a hoist, the combination with a driving shaft, of a series of alternately fixed and rotary brake elements coaxial with said shaft, a housing surrounding said elements and provided with air passages, 60 and vanes on said rotary elements adapted

to propel an air current through said housing to cool said brake elements.

5. In a hoist, the combination with a housing of a driving shaft rotatably mounted therewithin, fixed and rotary brake elements coaxial with said driving shaft, a governor weight controlled by the rate of rotation of said driving shaft for variably forcing said fixed and rotary brake elements into frictional engagement with each other, 70 and means on said governor weight for propelling an air current through said housing to cool said brake elements.

6. In a hoist, the combination with a driving shaft, of a series of rotary brake members secured to said shaft, a series of stationary brake members alternating with said rotary members, all of said members being capable of axial movement, means for applying spring pressure to one side of said 80 members, a rotating abutment on the opposite side of said members, means for relieving said spring pressure, and means for varying the position of said rotary abutment according to the speed of rotation.

7. In a hoist, the combination with a housing, of a driving shaft rotatably mounted therein, a member non-rotatably mounted on said driving shaft, a brake element non-rotatably mounted on said driving shaft, a second brake element non-rotatably secured to said housing and adapted to engage the first-mentioned brake element, a governor weight controlled by the rate of rotation of said driving shaft, and means 95 adapted to be moved by said governor weight to force the brake elements into contact with each other when said governor weight moves away from the first-mentioned member upon rotation of said governor weight relative to the member aforesaid.

8. In a hoist, the combination with a driving shaft, of a series of alternately fixed and rotary brake elements co-axial 105 with said shaft, a spring-operated sleeve adapted to maintain said brake elements in frictional engagement, a collar secured to said sleeve, a member rotatably mounted on said sleeve and having a cam engagement with said collar, and a lever operatively connected to said rotatable member and adapted to rotate the same to cause said collar to move said sleeve against the tension of its spring to release said brake elements.

In testimony whereof I affix my signature.

WILLIAM E. SIMPSON.
